FIG. 1 is a top isometric view of an input device for an electronic tablet showing the new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken line showing of various features of the input device for an electronic tablet in the figures is for environmental purposes only and forms no part of the claimed design.

1 Claim, 4 Drawing Sheets
